(57) **CLAIM**

The ornamental design for a toy car base, as shown and described.

DESCRIPTION

FIG. 1 is a right side view;

FIG. 2 is a left side view;

FIG. 3 is a top view;

FIG. 4 is a bottom view;

FIG. 5 is a front view;

FIG. 6 is a rear view;

FIG. 7 is a perspective top right side view; and,

FIG. 8 is a perspective bottom right side view.

The dash-dot broken lines immediately adjacent the solid-lined areas represent the bounds of the claim. All other broken lines illustrate the position of a toy car body on the toy car base. None of the broken lines form a part of the claimed design.
